[57] CLAIM

The ornamental design for a wrist watch, substantially as shown and described.

DESCRIPTION

FIG. 1 is a front elevational view of a wrist watch showing my new design;

FIG. 2 is a top plan view thereof;

FIG. 3 is a right side elevational view thereof, the left side elevational view being identical to the right side elevational view;

FIG. 4 is a bottom plan view thereof;

FIG. 5 is a rear elevational view thereof; and

FIG. 6 is a perspective view thereof.

FIG.1

FIG.3

FIG.2
